UNITED STATES PATENT OFFICE.

CHARLES A. PALMGREN, OF CHICAGO, ILLINOIS.

BORING AND TURNING BAR AND BAR-HOLDER.

1,014,412.

Specification of Letters Patent.

Patented Jan. 9, 1912.

Application filed December 24, 1910. Serial No. 599,141.

To all whom it may concern:

Be it known that I, CHARLES A. PALMGREN, a resident of Chicago, in the county of Cook and State of Illinois, have invented 5 a new and useful Improvement in Boring and Turning Bars and Bar-Holders, of which the following is a full, clear, and exact description, reference being had to the accompanying drawings, forming part of this 10 specification, in which—

Figure 1 is a view showing an end elevation of an attachment embodying my invention applied to a lathe; Fig. 2 is a side elevation of the attachment; Fig. 3 is a plan view 15 of the same partly in section; and Fig. 4 is a section on the line IV—IV of Fig. 3; Fig. 5 is a detail view similar to the left hand end of Fig. 3, showing the sleeve reversed to secure a tool at right angles to the boring bar. 20 My invention is designed to provide a boring bar and holder of improved character which can be readily attached to lathes; which can be readily and quickly adjusted; which can be used with tools of varying 25 forms; and which can be attached to lathes in such a manner as to insure great firmness and rigidity.

A further object of my invention is to provide a boring bar of this character which 30 can be used to equal advantage for turning; which can be made in any desired size to suit different sizes of lathe on the market; and which will permit the tools to be readily changed to make either an outside or an in- 35 side cut.

In the accompanying drawings, the numeral 2 designates a lathe bed having therewithin the usual guide 3, on which is mounted the slide rest 4, having the usual feed devices 40 5. The slide rest is provided in its upper face with a T-groove 6, by means of which my improved attachment is secured thereto.

7 designates the bar holder which is of 45 segmental form with a concave upper edge 8 and a convex lower edge 9, the latter having a concave bearing in the upper face of a block 10, which is seated on the slide rest 4. The holder is secured to the slide rest, preferably by means of two bolts 11, 50 having two different size heads at their lower ends which engage the T-slot 6, which may be of two sizes, of the slide rest, and which extend upwardly through the block 10, and through the holder 7, being secured 55 by nuts 12 at their upper ends with convex face washers 13 interposed between the nuts

and the concave upper edge 8 of the holder. The holes in the holder for these bolts are slotted, as shown at 11^a, in order to permit of the necessary range of adjustment of the 60 holder. The forward end portion of the holder is formed with a split sleeve portion 14, having clamping lugs 15, and tightening screws 16. The sleeve portion being located approximately central of the edge portions 65 8 and 9.

17 is the sleeve of the boring bar, which is adjustably secured in the sleeve portion of the holder by means of the clamping lugs 15, and screws 16, and which is open at both 70 ends and slotted at both ends for the reception of the cutting tool.

18 is a bar extending longitudinally through the sleeve and which is prevented from rotating therein by means of a swivel 75 clamping jaw at its front end. The front or cutting end portion of the sleeve 17 is slotted back from its forward end at opposite sides, as shown at 20, the rear walls of these slots being inclined or beveled, as indicated at 21, 80 to form clamping seats for the tool 22. The forward end portion of the bar 18 also has a slot 23, extending diametrically therethrough to receive the tool 22 and also the clamping jaw 24. This clamping jaw has 85 a convex face 25 and also has a straight clamping face 26, to clamp the tool. The jaw 24 is loosely seated in the slot of the bar 18 by means of the transverse pin 27. The rear end portion of the bar 18 projects beyond the end of the sleeve 17, and is threaded 90 to receive a nut 28 having a lever handle extension 29.

The clamping jaw arrangement 24 prevents rotation of the bar 18, whereby when 95 the nut 28 is screwed up and is turned by means of the lever handle, the bar 18 will be moved endwise to either clamp or release the tool, the tool being clamped between the face 26 of the jaw 24 and the inclined walls 100 21 of the slot 20.

Vertical adjustment of the bar may be quickly and rapidly effected by slackening the nuts 12. The attachment during this adjustment is at all times parallel to the bed 105 of the lathe, thereby doing away with any tilting movement and insuring at all times a perfect and true cutting bore, without readjusting the tool in the holder. By means of the two bolts 11, the attachment is 110 securely held to the lathe with great firmness and rigidity, being much superior in

this respect to securing the bar in a tool post. The construction enables the operator to at any time make quick changes. It will be further noted that there are no 5 screw clamps which can be tightened by the cutting action of the tool, thereby making it difficult to remove the tool. It will also be noted that the bar is equally adapted for use either in boring or turning; the ball 10 joint connection of the holder provides means for insuring rapid and accurate inside work; any suitable piece of steel can be used as a cutting tool without special blacksmith or machine work to fit it, other 15 than the grinding of the proper cutting edge; the tool can be changed from an outside to an inside cut by simply reversing it in the holder; and the holder will hold any boring tool either round, square or hexagonal. The bar holder may be made of any 20 size required to suit the particular lathe.

I preferably also provide the opposite end of the sleeve 17 with tool slots 30, having substantially vertical walls 31. By 25 these provisions, I enable the sleeve to be reversed end for end with respect to the rod, so that the tool may be held in a straight position, instead of inclined, as shown in Fig. 3, the tool in this case being 30 clamped between the jaw 24 and the straight walls 31 of the slots 30. The jaw 24 being pivoted, is enabled to adjust itself to the surface of the tool and thus provide a rigid and secure clamp.

35 It will be obvious that various changes may be made in the details of construction and arrangement of the several parts, without departing from the spirit and scope of my invention as defined in the appended 40 claims.

I claim:

1. The combination with a lathe slide rest having a concave bearing, of a boring bar holder having concaved and convexed 45 faces, the convex face fitting said bearing, securing bolts engaging the slide rest and arranged to secure the holder to the slide rest by engagement with the concaved face and also to hold it in different adjusted 50 positions on said bearing, and a boring bar intermediate of said faces; substantially as described.

2. The combination with a lathe slide rest, of a bearing piece seated on the slide

rest and having a concaved bearing surface, 55 a tool bar holder having a portion of segmental form provided with concaved and convexed faces, the convexed face adjustably engaging said bearing surface, a plurality of securing bolts engaging the slide 60 rest and passing upwardly through said piece and through slots in the holder, and having clamping means at their upper ends engaging the concaved face, and a sleeve at one end of the tool bar holder having 65 its axis intermediate of the concaved and convexed faces thereof; substantially as described.

3. A boring bar comprising a sleeve having slots at its end, a bar extending longitudinally through said sleeve and having a slotted end portion, a tool holding jaw pivoted thereto and within the slotted end portion of the bar and extending into the slots of the sleeve, and means for effecting 75 a longitudinal movement of the bar within the sleeve to clamp the tool between the jaw and the sleeve; substantially as described.

4. The combination with a lathe slide 80 rest, of a bearing piece seated on the slide rest and having a concaved bearing surface, a tool bar holder having a portion of segmental form provided with concaved and convexed surfaces, the convexed surface engaging said bearing surface, the radius of 85 said surfaces being such that the tool bar holder is within a circle which is coincident with said surfaces; substantially as described.

5. The combination with a lathe slide 90 rest, of a bearing piece seating on the rest and having a concaved bearing surface, a tool bar holder having a portion of segmental form provided with a convexed 95 surface, the convexed surface on the tool bar holder engaging the concaved bearing surface on the bearing face, the radii of said surfaces being such that the tool bar holder is within the circle which is coincident with 100 said surfaces; substantially as described.

In testimony whereof, I have hereunto set my hand.

C. A. PALMGREN.
